UNITED STATES PATENT OFFICE.

IDA P. RIEGER, OF NEW YORK, N. Y., ASSIGNOR TO FELIX MEYER, OF NEW YORK, N. Y.

DESIGN FOR LACE.

50,895.

Specification for Design.

Patented June 5, 1917.

Application filed April 23, 1917. Serial No. 164,069. Term of patent 3½ years.

To all whom it may concern:

Be it known that I, Ida P. RIEGER, a citizen of Switzerland, residing at New York, New York county, and State of New York, have invented a certain new, original, and ornamental Design for Lace, of which the following is a specification.

Said design consists in a lace pattern, as shown in the accompanying drawings.

What I claim is:

The design for lace as herein shown.

In witness whereof, I have hereunto set my hand and seal at New York, N. Y., this 21st day of April, A. D. nineteen hundred and seventeen.

IDA P. RIEGER. [L. S.]
